GERSON ISENBERG, OF NEW YORK, N. Y., ASSIGNOR TO ISENBERG CIGAR COMPANY,
OF WHEELING, WEST VIRGINIA, A FIRM.

ADVERTISING DEVICE.

1,144,707.

Specification of Letters Patent. Patented June 29, 1915.

Application filed November 1, 1913. Serial No. 798,746.

To all whom it may concern:

Be it known that I, GERSON ISENBERG, a citizen of the United States of America, and resident of New York, county of New York, and State of New York, have invented certain new and useful Improvements in Advertising Devices, of which the following is a specification.

This invention relates to an article in the nature of an advertising novelty, souvenir, or the like, and it has for its primary object to provide a device which shall combine intrinsic worth or value with artistic merit and which shall be suggestive of the virtue of thrift, economy and frugality.

A further object is to provide an article of the character mentioned which is designed to forcibly impress upon the observer in an inoffensive manner the necessity for the exercise of prudence in the handling of money.

With these and other objects in view, the invention resides in the features of construction and arrangement of parts which will hereinafter be fully described, reference being had to the accompanying drawings, in which—

Figure 1 is a face view of the invention; Fig. 2 is a similar view of a modified form of the same; Fig. 3 is a cross section on the line 3—3, Fig. 1; Fig. 4 is a cross section on the line 4—4, Fig. 2; and Fig. 5 is a longitudinal section on the line 5—5, Fig. 1.

Referring to said drawings, in which like designating characters distinguish like parts throughout the several views—1 indicates a base or backing composed of any suitable material, preferably cardboard. Mounted on said base in any appropriate manner so that it will retain its folded or plaited form is a paper currency note 2 which is so plaited or folded as to cause it to assume a substantially triangular form in similitude to the body portion of a closed and unrolled umbrella, the exposed plaits or folds 3 being displayed in likeness to the folds of such umbrella, as shown in Fig. 1. For attaching the lower closely-folded end of the note or bill to the base 1, a ring, staple or like attaching device, as 4, which embraces said end without mutilation of the paper, is mounted in said backing in embracing relation to said end. Projecting outward from beneath the lower end of the note is the end of a match or other like slender article 5

in imitation of the spike of an umbrella; and projecting outward from beneath the upper or spread end of the note at a suitable point is a match or like slender strip of material 6 which constitutes a representation 60 of an umbrella handle. To further increase the likeness of the article to an umbrella the representation 7 of the projecting ends of ribs, and the representation 8 of a fastening ribbon or band, may be printed upon or 65 otherwise applied to the base 1 at properly positioned points.

As shown in Figs. 2 and 4, the exposed portion of the bill or note may be left plain and smooth, there being thus exposed a 70 portion which is more readily recognizable, as currency than when the bill or note is plaited or folded as in Fig. 1. The unexposed portion of the bill is folded neatly and is tucked in against the base 1 as shown 75 in Fig. 4.

Applied to the base 1, as by printing, stenciling, or painting, is preferably employed a catch-phrase 9, as "For a rainy day," illustrated in the drawings, suggestive 80 of the utility of the article.

It will be noted that the currency is not permanently attached to the base or backing against which it is mounted, but may readily be removed and employed in the 85 ordinary manner. Further, the currency is in no wise mutilated, the entire bill or note being utilized, the unexposed portions thereof being folded and tucked under for elevating the exposed portion above the surface 90 of the base, thus increasing the attractiveness and enhancing the artistic appearance of the article.

The article is designed for mounting in a frame with a glass face and is adapted for 95 use by savings banks and like institutions for encouraging the laying up of savings and a spirit of thrift among its customers and depositors, and for various kindred uses.

Having thus described my invention, what I claim as new, and desire to secure by Letters Patent, is—

1. A novelty comprising a suitable backing, a currency note folded into substantially triangular form mounted on said backing, said note having the major portion thereof folded under so that the exposed portion is elevated above the surface of said backing, and strips of a different material 105 110

- projecting outward from the opposite ends of the folded note, the said note and strips presenting an appearance in similitude to a closed unrolled umbrella.
- 5 2. A novelty comprising a suitable backing, a currency note folded into substantially triangular form mounted on said backing, said note having the major portion thereof folded under so that the exposed portion is elevated above the surface of said backing, said note presenting an appear-

ance in similitude to the body of an umbrella, and means applied to said backing in contiguity to said note to simulate parts of an umbrella accessory to the body.

15

In testimony whereof, I affix my signature in presence of two subscribing witnesses.

GERSON ISENBERG.
